FIG. 5

FIG. 6

FIG. 7

FIG. 3

FIG. 2

FIGURE 1 is a side view of the piezoelectrically ignited gas torch in accordance with the present invention;

FIGURE 2 is a view similar to FIGURE 1 showing the opposite side of said gas torch;

FIGURE 3 is a top view of the gas torch;

FIGURE 4 is a bottom view of the gas torch;

FIGURE 5 is an end view of the rear end of said torch;

FIGURE 6 is a fragmentary side view showing a modification of the rear end portion of the gas torch, the remaining portion undisclosed in FIGURE 6 is the same as that shown in the other figures; and

FIGURE 7 is an end view of the gas torch shown in FIGURE 6.

This application is a continuation-in-part of application, Ser. No. D6,235, filed Mar. 15, 1967, for Piezoelectrically Ignited Gas Torch, now abandoned.

I claim:

The ornamental design for a piezoelectrically ignited gas torch, substantially as shown and described.
